LEVELING MECHANISM FOR GAS HOLDERS
AND SIMILAR APPARATUS

John H. Wiggins, Chicago, Ill.

Application June 19, 1943, Serial No. 491,744

1 Claim. (Cl. 48—176)

This invention relates to apparatus of the kind that comprise a stationary tank or container, and a vertically-movable part that constitutes the top wall or roof of a gas chamber, my invention being applicable to gas holders of the type that are provided with a vertically-movable bell, and gas and/or liquid-storage tanks of the type that are provided with a "lifter" roof or vertically-movable top part that is adapted to rise and fall, and thus vary the internal volume of the gas space of the apparatus.

One object of my present invention is to provide an improved leveling mechanism, or balancing mechanism, for the vertically-movable part of an apparatus of the general type mentioned, which, in addition to maintaining said vertically-movable part in a level position, without danger of wobbling or incipient tipping, is of simple design and easy to build and install.

Another object is to provide a leveling or balancing mechanism for structures of the kind referred to, whose coacting parts are arranged on the exterior of the apparatus, at a point below the bell, roof, or other vertically-movable part controlled by said mechanism; and

Still another object of my invention is to decrease the number of parts required for attaining proper balance of a gas holder bell or lifter roof of relatively great diameter.

Figure 1 of the drawings is a side elevational view, illustrating my invention embodied in a storage tank provided with a lifter type roof.

Figure 2 is a top plan view of the apparatus.

Figure 3 is a fragmentary view, showing in front elevation, the sheave, pulley, or wheel, over which travel all of the flexible members on which the weight or other tension means exerts a pull.

Figure 4 is a top plan view of the parts shown in Figure 3; and

Figure 5 is a side elevational view of the parts shown in Figure 3.

In the accompanying drawings, which show the preferred form of my present invention, A designates the stationary tank or container of the apparatus, B designates the vertically-movable part or lifter roof, B' designates a gas-tight sealing device attached to the side wall of the tank and to a depending side wall portion of the roof, C, C' and C² designate flexible members, such as cables or chains, attached to said part B and arranged so as to maintain said part in a level position, and D designates a weight, spring or other means that exerts a load or pull on the flexible members C, C' and C², and nor-

mally holds them in tension. In apparatus of the kind to which my invention is particularly applicable, the bell, lifter roof, or other vertically-movable part B, projects upwardly above the top edge of the tank A, with the result that it is constantly subjected to wind pressures, which exert oscillatory forces on same. Accordingly, in order to prevent said vertically-movable part from wobbling, it is necessary that the leveling or balancing mechanism be of such design or construction, that it prevents incipient tipping of said vertically-movable part, and gives a dampening effect to any synchronous loading. I attain this highly desirable result by arranging and combining the flexible members C, C', C² and the weight or tension means D, so that when the vertically-movable part B is level, all of said flexible members are of equal tension and the load or force of the means D is applied evenly to all of said flexible members, and if the part B starts to tilt or tip, thus causing one of the flexible members to become slack, the load or force of the means D is instantly removed from said slackened flexible member and applied to the other flexible members to increase the tightness of same, and thus restore the part B to its level position.

In the form of my invention herein illustrated, the vertically-movable part B is provided at its peripheral edge with three equally spaced, depending legs, E, E' and E² that have offsets x at their lower ends, to which are attached the flexible members C, C' and C², respectively. The flexible member C leads upwardly from the offset at the lower end of the leg E, over a vertically-disposed sheave, pulley or wheel 1, carried by a bracket or other suitable supporting structure on the side wall of the tank A, and after traveling over said sheave, leads downwardly from same to the means D which is herein illustrated as a weight that is securely fastened to the end of the flexible member C. The flexible member C' leads upwardly from the offset at the lower end of the leg E' to a vertically-disposed guide pulley 2, carried by the side wall of the tank, and after passing over said guide pulley, the member C' extends in a horizontal direction around the tank, over horizontally-disposed guide pulleys 2^a and 2^b to the sheave 1, over which it passes along side of or parallel to the flexible member C. Instead of being attached to the weight D, the flexible member C' is attached to the flexible member C at a point between the weight D and the single sheave 1, over which said two flexible members C and C' travel side by side.

It will, of course, be understood that the horizontally-disposed guide pulleys 2^a and 2^b are carried by brackets or other suitable supporting devices on the side wall of the tank A. The third flexible member C^2 , which is located at the opposite side of the tank, as shown in Figure 2, leads upwardly from the lower end of the depending leg E^2 on the part B, to a vertically-disposed guide pulley 2 , on the tank side wall, and thence, extends in a horizontal direction around the tank over guide pulleys 2^a and 2^b , to the sheave 1 , over which said flexible member C^2 passes along side of the flexible member C, to which it is fastened at the point where the flexible member C' is joined to the member C. It will thus be seen that in my improved leveling or balancing mechanism, only three flexible members and a single weight are employed to maintain the vertically-movable part B of the apparatus in a perfectly level position. The three flexible members travel side by side over a single sheave 1 , and are tied together as one at said sheave, by the friction of said flexible members on said sheave. They are also fastened to the weight D, or are joined together, at a point beyond the sheave 1 . Instead of forming the flexible members C, C' and C^2 from cables, as herein shown, said members could be formed from chains, and the sheave 1 could be provided with three cogs, or three sets of sprocket teeth for receiving said chains. I have found, however, that cables are perfectly satisfactory, as their frictional contact or engagement with the sheave 1 is great enough to cause the load of the weight D to be equally distributed to the three flexible members when the roof B is floating level without foreign loads, and the instant said roof starts to tilt or tip, the resulting slackening off of one flexible member, causes the full load of the weight to be exerted on the other two flexible members in a direction to bring the roof back to its level position.

While I prefer to lead the flexible members C, C' and C^2 upwardly from depending legs on the vertically-movable part of the apparatus, and thence, in a horizontal direction around the tank to a point where said flexible members converge in advance of their point of connection with the weight D, this is not absolutely essential, as my invention contemplates various other ways of attaching said flexible members to the vertically-movable part of the apparatus, and various other ways of disposing and guiding said flexible members. The essential thing is, that the flexible members, in conjunction with the means D, exert a pull on the vertically-movable

part of the apparatus, in a vertical direction, and so long as this result is attained, the particular arrangement, location, or direction of travel of the flexible members is immaterial.

5 The main advantage of my improved mechanism, of course, is that it effectively holds a gas bell or lifter roof perfectly level, and prevents wobbling of same, even though said vertically-movable part is constantly subjected to 10 shifting wind pressure, due to the fact that the flexible members and weight are combined with said part in such a manner that the instant said part starts to tilt, the load of the weight is redistributed and applied to the flexible members 15 instantly in such a manner that the tendency to tip is checked or overcome before actual tipping occurs.

Another desirable feature of my improved mechanism is that all of the co-acting parts of 20 said mechanism are located below the top of the bell, lifter roof, or other part controlled by said mechanism. The above described characteristics, coupled with the fact that the mechanism is inexpensive to build, easy to install and comprises only a relatively few parts, makes said mechanism a decided improvement over the leveling mechanisms heretofore used for balancing gas bells and lifter roofs of large diameter. While I have herein described and illustrated 25 my invention in connection with a gas bell or lifter roof, I wish it to be understood that my invention is applicable to various other kinds of apparatus or structures that comprise a vertically-movable part of relatively great diameter, which it is necessary or desirable to maintain in a horizontal plane while said part rises and falls.

Having thus described my invention, what 30 I claim as new and desire to secure by Letters 35 Patent is:

40 A storage tank provided with a lifter type roof, depending portions on said roof, flexible members leading upwardly from the lower ends of said depending portions, sheaves for said 45 flexible members located on the tank side wall above the highest point of upward travel of the lower ends of said depending portions and vertically-disposed in relation to the points of attachment of said flexible members thereto, said flexible members extending individually upwardly and around individual sheaves, then horizontally and around a common sheave, and then downwardly, being united together below said common sheave, and carrying a weight below their union. 50 55

JOHN H. WIGGINS.
